UNITED STATES PATENT OFFICE.

JOSEPH BRANDWOOD, OF NEWTON, MASSACHUSETTS.

APPARATUS FOR THE CONTINUOUS TREATMENT OF TEXTILE FIBERS IN SKEIN FORM.

Application filed September 21, 1925. Serial No. 57,506.

To all whom it may concern:

Be it known that I, JOSEPH BRANDWOOD, a subject of the King of Great Britain, residing at Newton, in the county of Middlesex and State of Massachusetts, have invented certain new and useful Improvements in Apparatus for the Continuous Treatment of Textile Fibers in Skein Form, of which the following is a specification.

10 This invention relates to improvements in apparatus for the continuous treatment of textile fibers in skein form. More particularly it relates to apparatus for subjecting material, which may for example be in the 15 form of skeins or hanks, to the action of any desired fluid, as by spraying a liquid upon it, and meanwhile moving the skein about in its position, so that various parts of it are subjected to the action of the fluid, 20 and also advancing the skein through the zone of action of the fluid, or through the successive zones of action of different fluids, and thence out from the apparatus. Thus it provides for exposing each skein thoroughly 25 for a predetermined time to treatment by each successive fluid.

The invention is concerned with apparatus for holding and manipulating the skeins in relation to the fluid, rather than 30 with the particular materials treated, or which constitute the treating substances. Therefore, in general the material treated may be of any sort, such as cotton, wool, silk or artificial fiber; the fluid may be applied in any manner; and in the case of 35 application by spraying may be applied externally or internally or both, with respect to the skein; and the purpose of the treatment may be for the ordinary textile operations of bleaching, dyeing or washing, or 40 for other chemical treatments such as are suitable for dealing with cellulose. Likewise, the fluid is not necessarily a liquid, but by jets of air or some other gas, the 45 apparatus can be used for drying, or oxidizing, or subjecting the material otherwise to the operation of such other gas.

It has already been proposed to hang a 50 succession of skeins side by side upon a single rod, and then to move a succession of such rods sidewise through zones where the skeins thereon are treated. The invention provides improved means for this, with 55 more perfect operation, greater capacity of output, simpler mechanism, and less requirement for strength of parts and for power

than any previous apparatus known to me for this purpose. Each rod rests, at each end, on and between a pair of rotating wheels which communicate their rotation to the rod so that the rod rotates; and each skein depending from the rod is thus made to travel about in its own position by each part of it passing up to, over and down from the rod, above which may be the spray of treating fluid. This is old; but to advance the rods sidewise from time to time, as is necessary for their progression through the zone, it has been proposed to have a rail running under all of the rod ends at each side, and periodically to lift them all by these rails and transplant them one step laterally. This entails a powerful lifting effort periodically with strong rails to support all of the yarn and all of the rods at once; and as the supporting and driving wheels are set in gangs, adjacent gangs rotating oppositely, it also involves the holding of a rod and its load and space inactive, while it is positioned between the gangs rotating in opposite directions. This arrangement also entails the disadvantage that the rotation of yarn in either particular direction has to be unduly long continued before the reversal occurs. The improvement provides for making the reversals at short intervals; eliminates the inactive position between the two directions of rotation; eliminates the need for powerful side rails heretofore thought necessary for lifting all of the materials and rods at once, together with the apparatus for lifting such rails; and provides means by which each rod is advanced by being rolled sidewise over its support, thus taking it one step through the apparatus with a minimum of total lifting effort and with a power exertion which is subdivided and distributed throughout the apparatus, being localized at the places where the work is done, and being applied to the whole machine by extremely simple apparatus located at one end thereof.

These aims are accomplished by providing a pawl at each rod-end position which at the proper time simply pushes that rod-end in the direction in which it is to advance, and then returns to position for pushing the next rod through the same step. When so pushed the rod climbs up out of the valley between the two supporting wheels or rollers rolling over one of

them to settle down between that one and the next one ahead. The pawl which pushed it, when returning, passes under the rod next to the rear, which has likewise and simultaneously moved forward into the place of the one first mentioned, yielding so as not to affect this rod while moving backward. While various constructions may be employed for this, the particular 10 style illustrated is a horizontal thrust bar at each side of the machine, running under the rod-ends, with a pawl at each rod position comprising a body pivoted on the bar below the level of the rods, having an upstanding finger to engage the rod next in front of it, a depending balance weight heavy enough to hold the finger normally upstanding, and a stop pin which by preventing finger rotation 15 holds the finger rigid when the bar and finger are thrust forward, so that the rod is thrust forward by the finger, but permits yielding rotation of the finger in the opposite direction to pass under the rod next 20 to the rear when the bar and its pivot are drawn backward. The bars are reciprocated endwise at proper times by a simple cam movement.

For the reversal of rotation, all supporting rollers are simultaneously reversed in their drive by a clutch mechanism, at intervals which can be predetermined as short as may be thought wise.

The invention may be applied to various 35 mechanisms, that chosen for illustration being one in which the fluid applied is a liquid sprayed on the top of the skeins as they pass over their rods. However, the spray or outflow of fluid might be otherwise applied; and variations may be made in other particulars from the specific apparatus which is shown. It is intended that the patent shall cover by suitable expression in the appended claims whatever 40 features of patentable novelty exist in the invention disclosed.

In the accompanying drawings:

Figure 1 is a side elevation of apparatus embodying the invention, showing the 50 power drive but with a considerable portion assumed to be broken out of the middle of the machine;

Figure 2 is an elevation of the drive end of the same;

Figure 3 is a side elevation of a fragment 55 of the middle part, on a larger scale, as on the line 3—3 of Figure 2, showing the mechanism for advancing the skein rods step by step through the apparatus;

Figure 4 is a plan of a portion of the same fragment; and

Figure 5 is an elevation of a fragment of the same, as on 5—5 of Figure 4.

Referring to the drawings, the skeins 65 which are being treated are marked 10 and

the fluid with which they are treated is represented as a liquid 12 issuing from spray pipes 14, one of which is above each rod 16 on which the skeins are mounted, it being understood that in action there may be a 70 succession of skeins filling the greater part of the space between the two collars 18 seen in Figure 2, only one of which skeins is there represented. A long series of these rods is arranged extending from right to 75 left in Figure 1, with individual rods 16 seen in Figure 2 positioned side by side and laden as indicated in Figure 1, each end of each rod resting on and in the valley between a pair of rotating rollers or friction drive wheels 20. These may be rotated at a slow and regular rate by any suitable means. The device shown is that each roller is on a shaft 24 whose gear 28 is turned slowly by one of a series of worms 26 distributed along shafts 30, 30', one of which extends along each side of the machine. Gearing 32 connects the shaft 30' at the left in Figure 2, with the shaft 30 at the right in Figure 2, which latter has direct 80 drive at the power end of the machine seen at the rear and right in Figure 1. At this end there are oppositely rotating drive pulleys 34, 36, which by clutch 38 may be placed in engagement with the shaft 30 to make it 85 rotate in either direction, both pulleys 34 and 36 being loose on shaft 30. But one of them 34, has its hub connected by gearing 40 with shaft 42 on which is a worm that drives gear 44 and its shaft 46 which runs 90 across the machine near the bottom and has identical cams 48, one at each side of the machine, for effecting the step by step advancement of the skein rods, and has a single cam 50 operating through roller 52 and lever 54 to move the clutch 38 so as to engage the shaft 30 either with drive pulley 34 or reverse drive pulley 36 or to disengage it from both for a brief pause. Therefore the 95 rod rotating rolls 20 are driven by direct 100 connection from the power 34, 36, in either direction, with a pause at reversal, while the reversing mechanism itself and the mechanism for advancing the rods are operated constantly and at a regular 105 rate in the same direction.

By the cam 50 reversal of the rotation of the skein carrying rod 16 can be predetermined to be as often as desired, and rotation 110 may continue for as many revolutions in each direction as desired (by virtue of the differential time element which can be introduced through the train of gearing 40), as compared with the number of rotations 115 occurring meanwhile of the rod.

As the cams 48 and 50 are on the same shaft, it is possible by suitable design of their faces to make any desired arrangement as regards the time when the skein rods are advanced, with respect to the direction in 120 125 130

which the skein rods and their drive rollers are rotating. In practice it appears that no attention need be paid to this but that the invention operates well whether the drive rods are rotating in the direction in which the rods are to be advanced or are rotating reversely; and the cam illustrated is arranged for one shift to occur under each of these conditions. The shift is accomplished by the pressure of the cam 48 upon its roller 49 which operates its lever 56 to move the thrust bars 58, one of which extends along the whole length on each side of the machine, in the direction of the arrow in Figure 1, which is the direction for advancing the rods 16 one step the bar being then returned by spring 57. This advancement is accomplished by the device which is shown more in detail in Figures 3-5. The thrust bar, which is conveniently mounted on rollers 60, has a series of studs or pivot pins 62, one for each skein rod position, on each of which is mounted a pawl comprising a body having an upstanding finger 64 and a depending part or tail 66 so arranged that the weight of the tail tends to hold the finger upright. A stop pin 68 for each, rigid in the thrust bar 58, is in position to engage the said tail and thus to prevent the rotation of the finger 64 in backward direction about the pivot 62. The thrust bar 58 is conveniently made of two bars held together by the respective pivots as illustrated in Figure 5, with the pawls having fingers 64 and their tails 66 mounted between the two. As seen in Figures 4 and 5, the skein rods 16 may be of such length that they are confined within the sides 70 of the frame of the machine and thus are maintained approximately in alignment as they travel through the machine, thus also overlying the drive rollers 20 which project inward from the frame on each side of the machine as seen in Figure 5.

The thrust bars 58 are positioned further inward, close to the ends of the skein rods 16. The pins 62 and 68 thereon are positioned so that the following action takes place, illustrated in Figure 3. During their inactivity the fingers 64 rest in position A; and during their action they move successively through the positions B, C, and D, and then return to position E to position A, these later positions being indicated by dot and dash lines in Figure 3. The travel from A to B is lost motion and brings the finger into contact with the skein rod which is rotating at position *a-b*, as it rests on its drive rollers 20. The continuation of its advance causes the rod to move through position *c* to position *d-e* which it occupies while the finger 64 is at position D and as that finger returns from position D to A. On its advance, the tail of the pawl engages pin 68 and thus prevents the finger 64 from

being turned backward when it encounters the rod 16, and requires it to move that rod forward; but on its backward movement the finger 64 engages the rod 16 which was next behind it and can swing forward to clear 70 under it and then resume its erect position at A. While being pushed by the finger 64 the rod 16 can roll as much as is necessary on its friction driving roll 20, upon which its weight is carried in the main as it is 75 advanced, slipping meanwhile on the cam face of the finger 64. This is true whichever be the direction of rotation at the moment when the push forward of the thrust rod 58 and finger 64 occurs. If necessary suitable lubrication may be applied to the cam faces of the finger 64.

Thus the skein rods are advanced step by step through the apparatus having been introduced at one end by hand or by suitable 85 feeding apparatus and being received at the delivery end by hand or suitable feeding apparatus. The apparatus as a whole may be many feet long with the spray pipes 14, seen in Figure 1, divided into 90 groups delivering different fluids and with the drain trays 72 under them discharging their contents to different tanks each according to its kind.

This, however, is no feature of the invention, being a device already used in practice. And although the fluid is herein illustrated as being applied by spraying it will be understood that the same might be applied by immersion, as by making the trays, seen in Figure 1, in successive separate sections along the length of the machine, each sufficiently high so that the skeins 10 there seen would be immersed in the liquid contained therein. And variations in other respects may be made without departing from the scope of the invention and indicated in the appended claims.

I claim as my invention:

1. Apparatus for fluid treatment of material comprising rods for holding the material; supporting rollers between which the rods are positioned, arranged in series with the rods side by side; and means to push the rods against and over the said rollers, thereby advancing each along the series while supported by one of said rollers.

2. Apparatus for fluid treatment of material comprising rods for holding the material; supporting rollers between which the rods are positioned, arranged in series with the rods side by side; and pawls arranged to move the individual rods over their adjacent rollers thereby advancing the rods along the series.

3. Apparatus for fluid treatment of material comprising rods for holding the material; supporting rollers between which the rods are positioned, arranged in series with

the rods side by side; side bars extending along the series; pawls on the side bars, arranged to engage and move the rods over the rollers step by step along the series, and means to thrust the bars forward and backward along the series.

4. Apparatus for fluid treatment of material comprising rods for holding the material; supporting rollers between which the rods are positioned, arranged in series with the rods side by side; a series of pivoted fingers each positioned to press forward laterally on the end part of one of the rods to move it along the series, and mounted to pass backward idly by the next rod in series; and means to move the said fingers forward and backward.

5. Apparatus for fluid treatment of material comprising rods for holding the material; supporting rollers between which the rods are positioned, arranged in series with

the rods side by side; means to rotate the supporting rollers, and to reverse their rotation periodically; and means to push the rods against and over the said rollers, thereby advancing each along the series while supported by one of said rollers; at a period when the roller is rotating forward.

6. Apparatus for fluid treatment of material comprising rods for holding the material, supporting rollers between which the rods are positioned, arranged in series with the rods side by side; means to rotate the rollers, thereby rotating the rods; cam means to reverse the rotation periodically; and cam means adapted to act periodically to push the rods against and over their adjacent rollers thereby advancing the rods along the series.

Signed at Boston, Massachusetts, this 40 tenth day of September 1925.

JOSEPH BRANDWOOD.
